9 Claims. (Cl. 35—25)

1

This invention relates to ordnance and is illustrated as embodied in a machine for training crews in the loading of guns of large caliber.

In order to train gun crews in the loading of 5-inch naval guns, for example, it is common practice to provide loading machines which are used extensively in naval training stations and form part of the regular equipment on ships. Such machines simulate as nearly as practicable the rear end of the gun for the loading of which the crew is being trained and are so constructed and operated that the crew, after a short period of training on the machine, can, with very little further training, effectively load the gun. Machines now used for this purpose are practically duplicates of a considerable portion of the gun which the crew is being trained to load and are not only expensive but occupy a considerable amount of space.

When a 5-inch naval gun has completed the counter-recoil portion of its cycle it comes to rest, the breech block of the gun being held in a lowered or retracted position and the breech of the gun being open ready to receive ammunition which commonly comprises a projectile and a separate powder case which are placed upon a tray formed by telescoping extensions of a slide and a breech casing of the gun, said tray being in approximate alinement with the lower portion of the breech of the gun so that the projectile and case can be slid forward into the breech by a hydraulically operated rammer. When the gun is at rest, as above described, a head of the rammer is in a raised inoperative position spaced a considerable distance from the rear end of the ammunition tray, said head having moved to such position during the recoil of the gun so as to permit the powder case used in the previous firing of the gun to be ejected rearward along the tray and onto the floor of a turret in which the gun is usually mounted.

The gun is loaded at this stage of its cycle, the projectile and powder case being manually placed in the ammunition tray of the gun. Before placing the projectile and the powder case in the tray, one of the crew actuates a lever, commonly known as a rammer head lever, located above the rear end of the tray, to cause the rammer head to slide under spring action into a lowered position adjacent to the tray so that during subsequent forward movement of the rammer it will engage the rear end of the powder case and slide the case, together with the projectile, into the breech of the gun. The projectile and the powder case having been placed in

2

the tray and the rammer head having been moved to its lowered position, a lever positioned just above the rear end of the breech block is manually actuated by one of the gun crew, causing the rammer, the head of which is in engagement with the rear end of the powder case, to move forward, causing the projectile and the case to be driven into the breech. Just before entering the breech the rim of the powder case engages a pair of lugs, causing the breech block to be raised into battery position. As the breech block is moved into battery position it causes the rammer head to be raised slightly in order to avoid its being contacted by the gun during recoil of said gun, a stud secured to the rammer head being moved onto an inclined camway of the gun slide. The gun is fired from a central director station after the breech block has been locked in battery position.

20 During the recoil of the gun the rammer is moved to a retracted or rearward position and is then held stationary in said position, the head of the rammer being raised during its rearward movement by the above-mentioned rammer head 25 stud, which, during such movement, travels upward along said camway. As the gun starts its counter-recoil movement, the breech block is moved to its lowered retracted position, an extractor ejecting the empty powder case from the 30 gun by sliding it rearward along the tray and onto the turret floor.

When the gun is elevated above 35° the rear end of the gun slide moves into an arcuate recess of the turret floor, with the result that the 35 empty powder case, in being ejected, is prevented by the bottom of said recess from being thrown out of the tray. Accordingly, when the gun is elevated above 35° one of the gun crew has to remove the empty powder case manually from the 40 tray. After the powder case has been removed from the tray, the rammer head is lowered by spring action, as above explained, after one of the crew has actuated the rammer head actuating 45 lever. Another projectile and case are then placed in the tray and the rammer actuating lever is moved by one of the members of the crew to cause the hydraulically operated rammer to reload the gun, as above described.

It is an object of the present invention to provide a simple, inexpensive loading machine by the use of which a gun crew may be quickly and effectively trained in the loading of 5-inch guns, for example, such as above described.

With the above object in view, there is provided a practice loading machine comprising an

55

ammunition tray, means for locking the tray in ammunition supporting position, a receiver, a lever simulating a rammer actuating lever of the 5-inch gun, for example, and means movable in response to movement of the lever for releasing said locking means to permit the tray to retract from its ammunition supporting position to cause ammunition to be dumped into the receiver.

Since it is desirable to train crews in the loading of guns using two-part ammunition, the tray of the illustrative machine comprises a pair of trough-shaped trays arranged in alinement, a front tray being of suitable construction to receive a projectile and a rear tray being of suitable construction to receive a powder case. In order to dump the ammunition from the trays, each of said trays is split longitudinally along its central portion, the opposite halves of the trays being pivotally mounted for lateral movement away from each other upon a rigid frame which simulates the slide of the gun. The tray supporting frame is pivotally mounted for angular adjustment in elevation upon a pedestal simulating a trunnion block support of the gun, means being provided to secure the frame to said pedestal for each 5° angle change in elevation of the frame on the pedestal.

The opposite halves of the trays are constantly urged toward each other, into closed ammunition supporting positions, by springs, movement of said halves of the trays toward each other being limited by stops. Extending from the opposite halves of each of the trays are holding lugs which are engaged by latches to retain said halves of the trays in their closed positions against movement when weighted by a projectile and a powder case, the arrangement being such that the trays, after dumping the projectile and the powder case, are moved by the springs into their closed positions, the latches thereafter overriding said holding lugs to retain the trays closed. The projectile and the powder case are supported by the latched trays until mechanism operatively connecting the latches and a lever, which simulates a rammer actuating member of the gun, is manually actuated to cause the latches to be moved away from their associated holding lugs, thereby enabling the opposite halves of the trays to swing away from each other and thus to dump the projectile and the case into front and rear sections of the receiver, from which the projectile and case are later removed.

As above stated, it is necessary after firing the gun to move the head of the hydraulically operated rammer of the gun from a raised inoperative position to a lowered operative position adjacent to the ammunition tray of the gun so that when the rammer is actuated said head may operate against the rear end of the powder case to slide said case, and in front of it the projectile, into the breech of the gun. The rammer head of the gun is moved by a spring to its lowered operative position upon manually actuating a release member pivoted upon the frame above the rear end of the case receiving tray. In the operation of the gun the rammer head release member is actuated before placing ammunition in the tray of the gun and, in order that a crew may be trained on the machine in accordance with such practice, there is operatively connected to the mechanism through which the tray supporting latches are released, a slide which simulates the rammer head of the gun and is movable against spring action into a raised position away from the powder case sup-

porting tray upon release of said latches, the slide being held in its raised position by a detent.

After the trays have dumped the projectile and the case, they move back to their closed positions under the action of said springs, the latches being held away from the holding lugs of the trays until the rammer head simulating slide is released from its raised position upon actuating a lever which simulates the rammer head release member of the gun and operates the slide holding detent. It will therefore be apparent that if the practice crew fail to actuate the slide releasing lever before placing the projectile and the case in the trays, the unlocked trays, weighted by the ammunition, will immediately swing away from each other, causing the projectile and the case to be dumped into the receiver. When this occurs the crew will immediately realize its mistake.

In order to train the crew in the manual removal of the powder case from the tray to simulate the above-mentioned practice of manually removing the case from the tray of a gun elevated more than 35°, the illustrative machine, in accordance with a further feature of the present invention, is provided with means responsive to angular adjustment of the frame of the machine above a predetermined angle of elevation, for example, 35°, for causing the latches of the projectile supporting tray but not the latches of the case supporting tray to be moved away from the holding lugs of the respective trays in response to movement of the lever which simulates the rammer actuating lever of the gun, with the result that the projectile is dumped from the front tray but the powder case is not dumped from the rear tray. Accordingly, when the frame of the practice loading machine is elevated above 35°, one of the crew has to remove the powder case manually from the rear tray in accordance with the practice in the operation of the gun.

The above and various other features of the invention will be understood and appreciated from the following detailed description read in connection with the accompanying drawings, in which

Figs. 1 and 2 are side and plan views, respectively, partly broken away and partly in section, of the illustrative practice loading machine; Fig. 3 is a view on line III-III of Fig. 1, a powder case receiving tray of the machine being shown locked against movement;

Fig. 4 is a view corresponding in part to Fig. 3 but showing the powder case receiving tray unlocked so as to cause a case placed in said tray to be immediately dumped from the tray;

Fig. 5 is a section on line V-V of Fig. 3 when the frame of the machine has been adjusted above 35° in elevation;

Fig. 6 is a section, partly broken away, on line VI-VI of Fig. 2; and

Fig. 7 is a detail view, partly broken away, showing the arrangement of ammunition as positioned in the trays of the machine and also showing a portion of an ammunition receiver.

The illustrative loading machine comprises a rigid frame or carrier 20 (Figs. 1, 2 and 3) simulating a slide of a 5-inch naval gun, and comprising right and left flanged side plates 22, 24 and front and rear end plates 26 (Fig. 1), 28, said plates being welded or otherwise secured to each other. As best shown in Fig. 1, the right side plate 22 is of rectangular shape except for a depending portion 29 extending, for purposes hereinafter explained, below the left side plate 24.

Rigidly secured, through a plurality of braces 30, to the upper margin of the left side plate 24 is an inwardly extending ammunition shelf or ledge 31 the forward portion of which is inclined and the rear portion of which is horizontal when the frame 20 is in its horizontal position shown in Fig. 1.

Five-inch naval guns, for the practice loading of which the present machine has been provided, are commonly mounted in pairs on large craft, the illustrative frame 20 being similar to the slide upon which the left gun of each of said pairs recoils, said left gun, as in single 5-inch guns used on small craft, being loaded from the left side as viewed from the rear.

Bolted to circular bosses on the side plates 22, 24 of the frame 20 are trunnions 32 which simulate trunnions of the gun and are rotatably mounted in blocks 34 secured to a support or pedestal 36 fixed to a floor or deck 38 (Fig. 1). Legs of the trunnion block support 36 are rigidly secured to each other by a plurality of transverse headers.

The frame 20 may be manually rotated to a desired position in elevation about a common axis 40 (Figs. 2 and 3) of the trunnions 32 and is then secured in said position by threaded bolts 42 (Fig. 1) which fit in bores of the trunnion block support 36 and are screwed into aligned tapped holes 44 formed in arcuate bars 46 forming parts of depending rigid yokes 48, respectively, welded to the associated side plates 22, 24. The lines of centers of the holes 44 of the bars 46 are centered at the axis of the trunnions 32, said holes being so spaced that 5° elevation adjustments of the frame 20 on the trunnion block support 36 may be effected. The angular adjustment of the frame 20 upon the trunnion block support 36 simulates the elevation adjustment of the gun upon its trunnion block support. For purposes of description, the frame 20 may be said to have a centrally located longitudinal axis 50 (Figs. 1 and 2) extending lengthwise of the frame and intersecting the axis 40 of the trunnions 32 midway between the legs of the trunnion block support 36.

Secured to the side plates 22, 24 of the frame 20 are rear, center and front pairs of brackets 52 (Figs. 1, 2, 3 and 6), 54 (Figs. 1 and 2), 56 (Figs. 1, 2 and 6) in bores of which are supported aligned fulcrum pins 58, 60 and 62, respectively. Mounted for rotation upon the pins 58, 60 are bored bosses 64 (Figs. 2, 3, 4 and 6), 66 (Figs. 1 and 2) of a powder case receiving tray 68, said tray comprising two arcuate parts or halves 68a (Figs. 2, 3 and 4) which, when the tray 68 is in its case receiving and supporting position shown in Fig. 3, are spaced a slight distance from each other, forming at the bottom of the tray a longitudinal slot 70. The bosses 64 fit between spaced flanges of the brackets 52 and restrain the arcuate halves 68a of the tray 68 against lengthwise movement.

Mounted upon the pin 60 carried by the middle bracket 54 and upon the pin 62 carried by the front bracket 56 are bored bosses 72 (Figs. 1 and 2), 73 (Fig. 2), respectively, of a projectile receiving tray 74 (Figs. 1, 2 and 6) comprising two arcuate parts or halves 74a (Figs. 2, 3 and 4) which practically engage each other when the tray is in its projectile receiving and supporting position shown in Fig. 2. The bosses 72, 73 of the projectile receiving tray 74 fit between spaced flanges of the brackets 54, 56, respectively, and 75 in its closed position. For reasons hereinafter

insure against lengthwise movement of the tray upon the pins 60, 62.

The trays 68, 74 simulate the ammunition tray of the 5-inch gun, which tray, as previously stated, is formed by telescoping parts of the breech casing and the slide of the gun, ammunition comprising said projectile and powder case being forced lengthwise of the gun tray into the breech of the gun by a rammer.

- 10 In the illustrative loading machine, a projectile 76 (Figs. 1 and 7) and a loaded powder case 78 (Figs. 1, 3 and 7) are arranged upon the ledge 31 of the frame 20 in their proper lengthwise positions determined by a loading lug 80 (Figs. 1, 2 and 3) secured to the ledge 31, and are then rolled into the trays 74, 68, respectively, the loading motions on the part of the practice crew being practically identical with the motions of a gun crew presenting a projectile and powder case to the tray of the 5-inch gun.

The opposite halves 68a of the powder case receiving tray 68 are constantly urged toward each other into their closed positions, best shown in Figs. 3 and 4, by springs 82 (Figs. 1, 3, 4 and 6)

- 25 the lower ends of which are secured to brackets 84 (Figs. 1 and 3) welded to the rear plate 28 of the frame 20 and the upper ends of which are secured to depending flanges 86 (Figs. 3 and 4) at the forward ends of holding lugs 88 formed integral with the bosses 64 of the halves 68a of the tray 68, the tray being closed when the under faces of the holding lugs 88 are in engagement with stops 90 (Figs. 3, 4 and 6) secured to the brackets 52. The right and left halves 74a of the tray 74 are constantly urged into their closed positions, best shown in Fig. 2, by springs 92 (Figs. 1, 2 and 6) the lower ends of which are attached to depending portions 94 (Fig. 1) of a transverse header 96 (Figs. 1 and 2) of the frame 40 and the upper ends of which are secured to depending flanges 98 (Figs. 1, 2 and 6) of holding lugs 100 (Figs. 2 and 6) formed integral with the boss 73 of the tray 74, the halves 74a of said tray being moved toward each other by the action 45 of the springs 92 until under faces of the holding lugs 100 engage stops 102 secured to the bracket 56.

The trays 74, 68 are locked in their closed positions by front and rear pairs of latches 104 (Figs. 1, 2 and 6), 106, the front latches 104 being fixed 50 to longitudinal shafts 108 which are rotatably mounted in bearings supported by the front and rear brackets 56, 52 and also by bearings of a central bracket 110 (Figs. 1 and 2), each of the shafts being made in two parts joined by an 55 Oldham coupling 112. The rear latches 106 are normally coupled for movement with the shafts 108 through collars 114 which, as best shown in Fig. 5, are splined on the shafts and have flanges 116 which normally register in recesses 118 (Figs. 3, 4 and 5) of associated rear latches.

- 60 Fixed to the rear end of each of the shafts 108 is a lever 120 (Figs. 1, 2, 4, 5 and 6) having secured to it a strong spring 122 the lower end of which is attached to the bracket 84. The latches 106, 104 are constantly urged toward 65 associated holding lugs 88, 100 by the springs 122 operating through the levers 120 and the shafts 108, the latches 106 normally engaging faces 126 (Figs. 3 and 4) and shoulders 128 of the holding lugs 88 to maintain the powder case receiving tray 68 in its closed position, and the latches 104 engaging corresponding faces 130 (Fig. 2) and shoulders 132 of the holding lugs 100 to maintain the projectile receiving tray 74 70 in its closed position. For reasons hereinafter

explained, the latches 106 are constantly urged toward the associated holding lugs 88 by springs 134 (Figs. 3, 4 and 6) the inner ends of which fit in recesses 136 of the latches and the outer ends of which are held in position by studs 138 (Fig. 3) secured to the brackets 52.

As previously stated, the rammer of the above-identified 5-inch naval gun, through hydraulically operated mechanism, feeds the projectile and the powder case resting upon the gun tray into the breech of the gun upon downward movement of the above-referred to rammer-actuating lever which is identical in construction and arrangement with a lever 140 (Figs. 1, 2 and 3) pinned to a shaft 142 fulcrumed in brackets 144 secured to the side plates 22, 24 of the frame 20. Secured to the shaft 142 are a pair of arms 146 operatively connected by vertically arranged rods 148 to arms 150 secured to the shafts 108.

When the projectile and the powder case are chambered and the breech block of the above-identified 5-inch naval gun has been moved to battery position, the gun is fired from one of the director stations. As above explained, when the gun mounted in a ship turret and elevated less than 35° is fired, the empty powder case is ejected rearward along the gun tray and onto the turret floor, the rammer head of the gun at such time being held in a raised idle position a considerable distance from the gun tray so as to be out of the path of movement of the ejected powder case.

In the illustrative practice loading machine, when the lever 140 is depressed to simulate actuating the rammer to load the gun, the projectile 76 and the powder case 78 supported by the trays 74, 68 are quickly and effectively dumped from the trays by causing the latches 104, 106 to be moved away from their associated holding lugs 100, 88 against the action of the springs 122, 134, the projectile and the powder case falling into front and rear sections 152a (Figs. 1 and 2), 152b (Figs. 1, 2 and 3) of a receiver 152. The forward end of the receiver 152 is secured by one or more brackets 154 (Fig. 1) to the header 96, which may be considered part of the frame 20, and the rear end of the receiver is secured to said frame by brackets 156 (Figs. 1 and 3), 158 (Figs. 2 and 3), said receiver, as best shown in Fig. 3, being laterally inclined at approximately 10° to the horizontal and passing through an opening 160 (Figs. 2 and 3) in the side plate 22. The front and rear sections 152a, 152b of the receiver 152 are separated by a transverse plate 162 which is arranged in approximate alignment with the abutting ends of the trays 68, 74. The forward end of the receiver 152 is curved upward, as best shown in Fig. 1, in order that it may afford support for the nose portion of the projectile 76. It will be apparent that the trays 68, 74 are often inclined lengthwise at a considerable angle to the horizontal in order to simulate high angles of elevation of the gun. Accordingly, the transverse plate 162 and a rear end 164 (Figs. 2 and 3) of the receiver 152 extend upward almost to the trays, as best illustrated in Fig. 3, and have beveled ridges 166 (Figs. 3 and 7), thereby insuring that when the projectile and the powder case are dumped from the trays they shall fall into the sections 152a, 152b, respectively, of the receiver.

Secured to a sleeve 167 (Figs. 1 and 3) mounted upon a rod 168 (Figs. 1, 2 and 3) secured to depending bosses 170 of each of the front and rear sections 152a, 152b of the receiver 152 are

two abutments 172 and an arm 174 which is pivotally connected to a rod 176 slidable in a bore formed in a block 178 secured to the receiver. Surrounding each of the rods 176 and interposed between an associated block 178 and a lock nut threaded onto the rod 176 is a spring 180 (Figs. 2 and 3) which normally serves to retain the abutments 172 of each of the sections of the receiver 152 in their raised, operative positions above the floor of the receiver, clockwise movement (Fig. 3) of said abutments acted on by the spring being limited by the engagement of a collar 182, pinned to the rod, with the block. When the abutments 172 are in their raised, operative positions, downward movement of the projectile 76 and the powder case 78 in the sections 152a, 152b of the receiver 152 is limited by said abutments. The projectile 76 and the powder case 78 in engagement with the respective abutments 172 may be quickly released so as to enable them to roll to the lower ends of the sections 152a, 152b of the receiver by sliding the rods 176 to the right as viewed in Fig. 3 against the action of the springs 180, causing the abutments to move into slots 184 (Figs. 1 and 2) in the floor of the receiver. Arm slots 186 are formed in the lower end of each of the sections 152a, 152b of the receiver 152 in order to facilitate the manual removal of the projectile 76 and the powder case 78 from the lower ends of said sections. The projectile 76 and the powder case 78, after being removed from the receiver 152, are placed in cylinders (not shown) simulating ammunition hoists of the gun turret.

As above stated, when the rammer of the gun returns to its retracted position during recoil of the gun elevated at less than 35°, the rammer head is moved into a raised idle position spaced a considerable distance above the ammunition tray 40 of the gun, thereby enabling the ejected powder case to slide the full length of said tray and onto the turret floor. Furthermore, as above explained, it is necessary before operating the rammer for one of the crew to cause the rammer head to be moved into a lowered position adjacent to the rear end of the tray so that said rammer head during its forward operating stroke will slide the powder case and the projectile supported by the tray into the breech of the gun. 50 In order to lower the rammer head, the gun is provided with the above-mentioned mechanism comprising a lever which is commonly referred to as the rammer head release lever and is arranged above the rear end of the gun slide, movement of said lever permitting the rammer head to be moved under spring action into its lowered, operative position adjacent to the tray.

With a view to simulating the rammer head release lever of the gun, the illustrative machine 60 is provided with a lever 188 (Figs. 1, 2, 3 and 4) which is similar in construction and arrangement to said rammer head release lever and is secured to one end of a shaft 190 rotatably mounted in a horizontal bore of a bearing bracket 65 192 secured by bolts 194 (Figs. 2 and 3) to the rear plate 28 of the frame 20. Pinned to the other end of the shaft 190 is an arm 196 operatively connected through a link 198 to a bell-crank lever 200 fulcrumed on a pin 202 fixed to a bracket 204 which is secured by screws 206 to the rear plate 28 of the frame 20. A torsion spring 208 (Figs. 2, 3 and 4) encircling the shaft 190 and having one of its ends secured to the bracket 192 and its other end underlying the arm 70 196 constantly urges the bell-crank lever 200

clockwise, as viewed in Figs. 1 and 6, a detent or retaining finger 210 (Figs. 1, 3, 4 and 6) of the bell-crank lever 200 being forced against a slide 212 (Figs. 3, 4 and 6) which simulates the above-mentioned rammer head of the gun. The slide 212 is moved in vertical guideways 214 formed in the bracket 204 and is constantly urged downward by springs 216 which extends into recesses 218 of the slide and have their upper ends in engagement with angle bars 220 secured to the bracket. In the central part of the slide 212 is a recess 222 into which the finger 210 of the bell-crank lever 200 moves when said slide is moved to a raised position by mechanism hereinafter described, said finger operating as a detent to hold the slide in its raised position until it is released by one of the crew moving the lever 188 counterclockwise as viewed in Figs. 1 and 6.

In the outer end of the lever 120 (Figs. 3, 4 and 6), which is pinned to the left shaft 108 as viewed in Fig. 3, is a coupling pin 224 fitting in an elongated slot 226 (Figs. 3 and 4) in the lower end of a link 228 pivotally connected to a lever 230 which is secured to the rear end of a shaft 232 journaled in a bore of a bearing bracket 234 supported by the rear plate 28. The forward end of the shaft 232 has secured to it a lever 236 provided with a slot 238 (Figs. 3 and 4) in which registers a stud 240 secured to the lower end of the slide 212.

It will be noted that when the slide 212 is held in its raised position by the finger 210 the latches 104, 106 are held in their inoperative positions away from the holding lugs 88, 100 of the trays 68, 74, respectively, and therefore do not secure the trays in their closed or ammunition supporting positions. It is therefore necessary to cause the slide 212 to move downward into its lowered position adjacent to the tray 68 before the trays can support a projectile and powder case placed therein. It will thus be apparent that the crew practicing loading will immediately appreciate their mistake should they fail to cause the slide 212, which corresponds to the rammer head of the gun, to be lowered prior to placing the projectile 76 and the case 78 in the trays 74, 68, because the latches 104, 106, which, after the slide has been lowered, hold the trays in their ammunition supporting positions, will then be held away from the holding lugs 100, 88 of the trays through the above-described mechanism, with the result that the projectile and the case placed in said trays will immediately drop into the receiver.

As above explained, when the 5-inch naval gun is elevated above 35°, the empty powder case ejected from the gun, instead of sliding from the ammunition tray onto the turret floor as above described, stops in the rear end of the tray because it hits the bottom of an arcuate gun receiving recess in the floor of the turret and cannot slide out of the tray. Accordingly, one of the members of the gun crew has to remove the empty powder case manually from the tray. It is necessary to train the crew in this operation and accordingly there is provided mechanism which, when the axis 50 of the gun slide simulating frame 20 is disposed at an angle greater than 35° to the horizontal, upon actuating the hand lever 140 causes the tray 74 to dump the projectile 76 into the front section 152a of the receiver 152 but renders the latches 106 immovable from their tray supporting positions shown in Fig. 3, thereby preventing the powder case 78 from being dumped from the tray 68 and

making it necessary for one of the training crew manually to remove the case from said tray.

As above explained, each of the latches 106 has formed in its rear end the recess 118 in which fits the flange 116 of the associated collar 114 when the axis 50 of the frame 20 is inclined at less than 35° to the horizontal, said collar being splined for rotation with and slidably along the shaft 108 upon which it is mounted to permit the collar to be moved rearward away from the latch 106 to the position shown in Fig. 5. Each of the collars 114 has a circumferential groove 242 (Figs. 5 and 6) of suitable size to receive inwardly extending fingers 244 carried by a yoke 246 secured to a shaft 248 fulcrumed in bores of brackets 249 bolted to the side plates 22, 24. Pivotally connected to the left yoke 246, as viewed in Figs. 3 and 4, is a rod 251 (Figs. 1, 2, 5 and 6) the forward end of which is connected to an upstanding arm 250 secured to a shaft 252 rotatably supported in a bracket 254 secured to the side plate 24 of the frame 20. A horizontal arm 256 also secured to the shaft 252 carries a cam roll 258 shaped and arranged to fit in a cam groove 260 (Figs. 1 and 6) formed in a plate 262 bolted to the trunnion block support 36. When the frame 20 is rotated clockwise as viewed in Fig. 1 about the axis 40 of the trunnions 32 into a position in which the axis 50 of the frame is inclined at approximately 35° to the horizontal, the cam roll 258 moves into an elevated portion of the cam groove 260, causing the arm 250 to be rotated clockwise as viewed in Fig. 6 to move the rod 251 rearward, with the result that the yokes 246 (Figs. 5 and 6) withdraw the flanges 116 (Fig. 5) of the collars 114 from the recesses 118 of the latches 106. It will thus be apparent that when the frame 20 is thus inclined, the front latches 104 but not the rear latches 106 are operated upon downward movement of the rammer actuating lever 140, the springs 134 operating to insure against the displacement of the latches 106 from their tray supporting positions.

In practicing loading by the use of the illustrative machine, two members of the crew manually remove the projectile 76 and the powder case 78, respectively, from the above-mentioned cylinders (not shown) which simulate projectile and powder case hoists, place them on the ledge 31 of the frame 20, and roll them into the closed trays 74, 68 which are then supported, against movement under the weight of the projectile and the case, by the latches 104, 106. One of the crew then depresses the lever 140 simulating the rammer head actuating lever of the gun, causing the latches 104, 106 to be swung outward away from the holding lugs 100, 88 of the trays, with the result that the trays open, causing the projectile and the case to drop into the sections 152a, 152b of the receiver 152. The projectile 76 and the case 78 dropped into the receiver roll down the floor of the receiver until they strike the abutments 172, and later roll down to the lower end of the receiver upon movement of the rods 176 against the action of the springs 180, the crew removing the projectile and the case from the receiver by utilizing the arm slots 186 in the lower end of the receiver and thereafter placing the projectile and the case back into said cylinders.

Movement of the longitudinal shafts 108 to cause the projectile 76 and the case 78 to be dumped also causes, through the mechanism above described, the slide 204 to be moved to its

11

raised position, illustrated in Fig. 4, said slide being held raised by the detent or finger 210. Before placing the next projectile 16 and case 78 in the trays 74, 68, one of the crew actuates the lever 188, which simulates the rammer head release lever of the gun, to cause the slide 204, which simulates the rammer head of the gun, to be lowered and to permit the latches 104, 106 to be moved back into their tray supporting positions. Should the crew fail to release the slide 204 before placing the projectile 76 and the case 78 in the trays, said projectile and case, after rolling over the ledge 31, will immediately dump through the trays into the receiver 152. The crew then realizes that it has failed previously to actuate the lever 188 and takes steps to correct the error during the next loading operation.

As above explained, when the axis 50 of the frame 20 is positioned at a greater angle than 35° to the horizontal, the tray 68 is at all times locked in its case supporting position and one of the members of the crew has to remove the case manually from the tray.

It will be appreciated that in practicing loading on the above machine the crew go through the same motions as they go through when loading the above-mentioned gun, any errors made in said practice loading being readily noted and corrected.

Having described my invention, what I claim as new and desire to secure by Letters Patent of the United States is:

1. In a loading machine for training gun crews, a tray one portion of which is mounted for movement away from another portion thereof, means for locking against movement said one portion of the tray in ammunition supporting position, a lever, a slide, mechanism comprising said slide movable into one position in response to movement of said lever for rendering said locking means ineffective and thus causing ammunition placed upon the tray immediately to be dumped from said tray, a detent for locking said mechanism in said one position, and an arm for operating said detent to permit said mechanism comprising said slide to move into another position in which said means for locking said one portion of the tray in ammunition supporting position against movement is rendered operative.

2. In a loading machine for use in training gun crews, a rigid frame, trays which are supported by the frame and are constructed and arranged to receive a projectile and a powder case respectively, a receiver, said trays being movable with relation to the frame from ammunition receiving positions under the weight of the projectile and the powder case to cause said projectile and case to be dumped into the receiver, means for securing the trays in their ammunition receiving positions in the frame, mechanism for operating said means to cause the trays to move with relation to the frame, thereby causing the projectile and the case to be dumped from the trays into the receiver, and connections which comprise a lever and are operatively connected to said mechanism, said connections being constructed and arranged to render said means ineffective to support the trays against movement relatively to the frame, after the trays have dumped the projectile and the case, until said lever is manually actuated.

3. In a loading machine for use in training gun crews, a rigid frame, trays which are mounted for pivotal movement upon the frame and are constructed and arranged to support a projectile

12

and a powder case respectively, a pair of stops, springs for urging the trays when empty into ammunition supporting positions against the stops, latches for retaining the trays in their ammunition supporting positions, a receiver, means comprising a lever corresponding to a member actuating a rammer and adapted to move said latches to inoperative positions to enable the trays, weighted by the projectile and the case, 10 to pivot on the frame against the action of said springs, thereby causing the projectile and the case to be dumped into the receiver, a slide movable toward and away from the case supporting tray, mechanism responsive to movement of said lever for raising the slide to a remote position away from the case supporting tray upon movement of said latches to their inoperative positions, locking means for retaining said slide in said remote position and for retaining the latches 20 in their inoperative positions, and an arm, for releasing said locking means to cause the slide to be moved to a lowered position adjacent to the case receiving tray and to cause said latches to be moved back to their tray supporting positions.

4. In a loading machine for use in training gun crews, a rigid frame, a pedestal, a tray mounted upon the frame, said tray being constructed and arranged to receive a powder case, mechanism 30 for locking the tray against movement with relation to the frame, connections for operating said mechanism to cause said tray to dump the powder case, said frame being angularly movable upon the pedestal into different positions in elevation, and means responsive to said angular movement of the frame for rendering said connections inoperative when the frame is elevated above a predetermined angle.

5. In a loading machine for use in training gun crews, a tray for receiving a projectile, a tray for receiving a powder case, means for locking the first-named tray in a projectile receiving position, means for locking the second-named tray in a case receiving position, mechanism for releasing the first-named locking means to cause the projectile receiving tray to move to a retracted position, thereby causing said projectile to be dumped, mechanism for releasing the second-named locking means to cause the powder case receiving tray to move to a retracted position, thereby causing said powder case to be dumped, said trays being angularly adjustable as a unit into different positions with relation to the horizontal about an axis spaced from and extending transversely of said trays, and means responsive to adjustment of the trays above a predetermined angle about said axis for rendering inoperative the mechanism for releasing the powder case receiving tray.

6. In a loading machine for use in training gun crews, a rigid frame, trays which are supported by said frame and are constructed and arranged to receive a projectile and a powder case respectively, a receiver, said trays being mounted for movement with relation to the frame, means for securing the trays in projectile and case receiving positions in the frame, mechanism for releasing the trays for movement in the frame to cause the projectile and the case received by and supported in the trays to be dumped from said trays, a slide which is movable toward and away from the case receiving tray, means responsive to movement of said mechanism for moving said slide into a raised position away from the case receiving tray, and

means for holding the slide in its raised position and for retaining the trays released for dumping movement in the frame.

7. In a loading machine for use in training gun crews, a tray comprising two or more parts for receiving a projectile, a tray comprising two or more parts for receiving a powder case, said parts of each of the trays being mounted for relative movement to cause the projectile and the case to be dumped from the trays, mechanism for enabling the trays to be moved into different angularly adjusted positions in elevation, means for causing the parts of the projectile receiving tray to move relatively to each other when the trays are moved above a predetermined angle in elevation, and means for causing the parts of the powder case receiving tray to be held against relative movement when the trays are moved about said predetermined angle.

8. In a loading machine for use in training gun crews, a projectile receiving tray, a powder case receiving tray, means for locking the projectile receiving tray in a position in which it supports a projectile placed thereon, means for locking the powder case receiving tray in a position in which it supports a case placed thereon, mechanism for releasing said first-named locking means to cause the projectile receiving tray to dump the projectile, mechanism for releasing said second-named locking means to cause the powder case receiving tray to dump said case, mechanism for causing the trays to be moved into different angularly adjusted positions in elevation, and connections movable in response to movement of the trays above a predetermined angle in elevation for rendering inoperative said second-named mechanism to insure that the powder case cannot be dumped from its associated tray.

9. In a loading machine for use in training gun crews, a frame, said frame being mounted for angular adjustment into different positions

in elevation, projectile and powder case receiving trays supported by said frame, said trays being constructed and mounted to open under the weight of the projectile and the case, for dumping said projectile and case, latches movable from operative positions, in which they support the trays against movement and thereby cause the trays to support the projectile and the case, to inoperative positions, in which they afford no support for the trays and thereby permit the trays to dump the projectile and the case, manually operated connections for moving said latches from their operative to their inoperative positions to cause the projectile and the case to be dumped from the trays, and mechanism responsive to angular adjustment of the frame above a predetermined angle in elevation for causing the latches associated with the case receiving tray at all times to be retained in operative positions to insure against movement of said case receiving tray irrespective of movement of said manually operated connections.
